UNITED STATES PATENT OFFICE

KURT ELTZE, OF MANNHEIM-KAFERTAL, GERMANY, ASSIGNOR TO DAIMLER-BENZ AKTIENGESELLSCHAFT, OF STUTTGART-BERLIN, GERMANY, A COMPANY OF GERMANY

COMPRESSION-REDUCING DEVICE FOR INTERNAL-COMBUSTION ENGINES

Application filed December 20, 1928, Serial No. 327,439, and in Germany January 9, 1928.

The starting of internal combustion engines, more particularly of oil engines in which the fuel is injected without the aid of compressed air, is particularly difficult owing to the high compression pressures. It has already been proposed to simplify the operation for multi-cylinder engines by changing over one cylinder after the other to operate on full compression pressure by 10 automatic displacement of the cam shaft. A second method on which the present invention is also based consists in this, that the engine is first of all turned round without any compression whatever, that is to say with open inlet and exhaust valves, the engine being then changed over to operate on a low compression and some fuel is admitted, the ignition being initiated by means of the known auxiliary devices, such 15 as nitrated touch paper or electric sparking plugs. By a further change over the engine passes over to normal operation with full compression.

In this connection there is the difficulty 25 that the operator at the moment in which he is occupied in turning over the engine, has to displace the cam shaft by hand for effecting the change over to the reduced compression pressure. This drawback is removed according to the present invention 30 by causing the first adjustment of the cam shaft, that is to say for effecting the change over of the engine from operation with open inlet and exhaust valves to operation with reduced compression, to take place automatically. The second displacement of the 35 cam shaft when changing over from the reduced compression to full compression is then effected by hand. This does not cause any difficulties, since with the change over to reduced compression, fuel is already being applied and ignitions take place.

A constructional form of the compression 45 reducing device according to the invention is illustrated by way of example in the accompanying drawing, in which Fig. 1 is a longitudinal elevation in part section showing the position occupied by the cam shaft 50 at the commencement of starting, that is to

say when the inlet and exhaust valves are held open.

Fig. 2 is an enlarged longitudinal sectional view of the compression reducing device; and

Fig. 3 is a transverse sectional view of Fig. 2, showing the plate opening for the cam-shaft projection.

Referring to the drawing, the cam shaft *a* is under the action of a spring *b* which tends to displace it towards the right and against the bushing *d* and the cover *e*. The bushing *d* is rotatably mounted in the sleeve *f* which is screwed into the wall of the motor casing by means of a quick screw thread. The end of the bushing *d* which faces the cam shaft is turned out and the cavity thus formed is closed by means of the screwed on cover *e*. A prolongation of the cam shaft *a* passes into a bore in the disc *e*. On the said prolongation is provided the projection *c* by means of which the cam shaft *a* is supported upon the cover *e*, being pressed against the same by means of the spring *b*. The projection *c* is capable of passing through a slot in the cover *e*.

At the commencement of starting up, the engine is brought into the position wherein the projection *c* has already passed the slot in the cover *e* in the direction of rotation. In the case of a four-cycle engine, the projection will pass through the slot after approximately one revolution of the cam shaft or after two revolutions of the crank shaft. The cam shaft *a* then slides under the action of the spring *b* towards the right until the prolongation strikes against the boss *i* of the pin *h*. In this position of the cam shaft, the engine operates with reduced compression, some fuel being also supplied as described more fully above.

In order to effect the change over to a full compression, the sleeve *f* is screwed out somewhat by hand by means of a handle *g*, the cam shaft following under the pressure of the spring *b*.

If the engine is to be started again after having been stopped, then the starting device is put into operation in the following manner: By means of the pin *h* the cam

shaft is pressed against the action of the spring *b* to the left, until the projection *c* bears against the inner side, that is to say the right-hand side of the cover *e*. The bushing *d* is then turned until the slot in the cover *e* is in register with the projection *c*. As soon as the projection is passed through the slot the bushing *d* is turned in the opposite direction to the direction of rotation of the cam shaft, so far that the projection *c* rests upon the cover *e*. By turning the sleeve *f* by means of the handle *g*, the cam shaft is then moved still further towards the left into the position shown in the drawing.

15 What I claim is:—

1. A compression reducing device for reducing the compression pressure of internal combustion engines when starting up the same, comprising the combination with a cam shaft capable of axial displacement from a starting position to a normal running position, and cam shaft displacing means operatively connected to the cam shaft and tending to urge the cam shaft from its starting position to its normal running position, of a stationary retaining device adapted to hold the cam shaft in its starting position and to release the cam shaft after the latter has turned through a definite angle of rotation, so as to enable the cam shaft to move under the action of the said displacing means into its normal running position.

35 2. A compression reducing device for reducing the compression pressure of internal combustion engines when starting up the same, comprising the combination with a camshaft capable of axial displacement from a starting position to a normal running position and a cam shaft displacing means operatively connected to the cam shaft and tending to urge the cam shaft from its starting position to its normal running position, of a retaining device adapted to hold the cam shaft in its starting position and to release the cam shaft after the latter has turned through a definite angle of rotation and an abutment adapted to engage the cam shaft and hold it in a position intermediate of its starting and normal running positions on the release of the cam shaft by the said retaining device, said abutment being capable of displacement by hand in the direction of the cam shaft axis so as to enable the cam shaft to move from said intermediate position into its normal running position.

55 3. A compression reducing device for reducing the compression pressure of internal combustion engines when starting up the same, comprising the combination with a cam shaft capable of displacement from a starting position to a normal running position and yielding cam shaft displacing means operatively connected to the cam shaft and

tending to urge the cam shaft from its starting position to its normal running position, of a bushing mounted in the casing of the engine and having retaining means adapted to hold the cam shaft in its starting position and to release the cam shaft after the latter has turned through a definite angle of rotation, said bushing having a cavity into which the camshaft is capable of entering on its release by said retaining means and an abutment in said bushing adapted to engage the cam shaft for holding the latter in a position intermediate of its starting and normal running positions, said abutment being displaceable by hand in the direction of the cam shaft axis so as to enable the cam shaft to move from said intermediate position into its normal running position.

70 4. A compression reducing device for reducing the compression pressure of internal combustion engines when starting up the same, comprising the combination with a cam shaft capable of displacement from a starting position to a normal running position and yielding cam shaft displacing means operatively connected to the cam shaft and tending to urge the cam shaft from its starting position to its normal running position, of a bushing mounted in the casing of the engine and having retaining means adapted to hold the cam shaft in its starting position and to release the cam shaft after the latter has turned through a definite angle of rotation, said bushing having a cavity into which the cam shaft is capable of entering on its release by said retaining means and an abutment in said bushing adapted to engage the cam shaft for holding the latter in a position intermediate of its starting and normal running positions, said bushing, together with the abutment, being displaceable by hand in the direction of the cam shaft axis so as to enable the cam shaft to move from said intermediate position into its normal running position.

75 5. A compression reducing device for reducing the compression pressure of internal combustion engines when starting up the same, comprising the combination with a cam shaft capable of displacement from a starting position to a normal running position and yielding cam shaft displacing means operatively connected to the cam shaft and tending to urge the cam shaft from its starting position to its normal running position, of a sleeve having a quick screw thread screwed into the wall of the engine casing and having a handle for enabling it to be turned by hand, a bushing in said sleeve and having a cavity in one end thereof facing the cam shaft, a cover on said bushing over said cavity and having an aperture therein, a prolongation on the cam shaft capable of passing through said aper-

ture into the said cavity, a projection on said prolongation adapted to support the cam shaft against said cover against the action of the yielding displacing means, a slot in said cover through which said projection can enter, said bushing being rotatable in the sleeve for enabling its angular position to be adjusted with respect to said projection that the latter can enter the slot and allow the 10 prolongation to pass through the cover into the cavity after the cam shaft has turned through a definite angle, and an abutment in said bushing adapted to engage the said prolongation and hold the cam shaft in a 15 position intermediate of its starting and normal running positions.

6. A compression reducing device for reducing the compression pressure of internal combustion engines when starting up the 20 same, comprising the combination with a cam shaft capable of displacement from a starting position to a normal running position and yielding cam shaft displacing means operatively connected to the cam shaft and 25 tending to urge the cam shaft from its starting position to its normal running position, of a sleeve having a quick screw thread screwed into the wall of the engine casing and having a handle for enabling it to be 30 turned by hand, a bushing in said sleeve and having a cavity in one end thereof facing the cam shaft, a cover on said bushing over said cavity and having an aperture therein, a prolongation on the cam shaft capable of 35 passing through said aperture into the said cavity, a projection on said prolongation adapted to support the cam shaft against said cover against the action of the yielding displacing means, a slot in said cover 40 through which said projection can enter, said bushing being rotatable in the sleeve for enabling its angular position to be adjusted with respect to said projection that the latter can enter the slot and allow the 45 prolongation to pass through the cover into the cavity after the cam shaft has turned through a definite angle, and a pin in said bushing adapted to engage the said prolongation and hold the cam shaft in a position 50 intermediate of its starting and normal running positions, said pin being slideable in said bushing and capable of displacing the camshaft to a position with the projection on the prolongation outside said cover, so as 55 to enable the cam shaft to be returned to its starting position.

In testimony whereof I have signed my name to this specification.

KURT ELTZE.
